(57) **CLAIM**

The ornamental design for an ingot-shaped bottle, as shown and described herein.

DESCRIPTION

FIG. 1 is a perspective view of a ingot-shaped bottle showing the new design;

FIG. 2 is a front view thereof;

FIG. 3 is a back view thereof;

FIG. 4 is a right side view thereof, with the left side view being a mirror image of the right side view;

FIG. 5 is a top view thereof; and,

FIG. 6 is a bottom view thereof.

The broken lines in the drawings are included to show portions of the article that form no part of the claimed design.
